UNITED STATES PATENT OFFICE.

JOHN ENQUIST, OF MINNEAPOLIS, MINNESOTA.

COMBINATION CHAIR AND TELEPHONE STAND.

Application filed January 25, 1926. Serial No. 83,543.

My invention relates to combination chairs and telephone stands and has for an object to provide a structure by means of which the ordinary desk telephone may be conveniently supported and upon which the user may be seated while using the telephone.

Another object of the invention resides in providing a chair having a shelf mounted upon the rear legs thereof and extending 10 outwardly beyond one of said legs to form a telephone support.

A still further object of the invention resides in providing a pocket in the back of the chair for the reception of a telephone book which pocket becomes accessible 15 through a slot in said shelf.

A still further feature of the invention resides in providing a sliding tray which may be used for holding the telephone receiver when the same is not placed upon the hook of the telephone.

Other objects of the invention resides in the combination of parts and in the detailed construction thereof as illustrated and described in the following drawing and specification and as particularly pointed out in the claims.

In the drawings:

Fig. 1 is a perspective view of my improved combination chair and telephone stand in use.

Fig. 2 is a plan view of a portion of the structure shown in Fig. 1, with the telephone and book removed, and drawn to a somewhat enlarged scale.

Fig. 3 is a sectional view taken on line 3-3 of Fig. 2.

It has been found that the ordinary desk telephone is highly desirable for use in residences as well as in offices due to the fact that the same may be moved about while in use so as to give the user freedom of movement while telephoning. At the same time, a telephone is frequently installed in 40 stair landings and other inconspicuous and more or less useless portions of the house where the user may have a certain amount of privacy. In such portions of the house it frequently happens that there does not 45 exist sufficient space for the installation of furniture or fixtures for the support and seating of the user so that the telephone is frequently allowed to stand upon the floor or to be otherwise supported in a more or 50 less unsatisfactory manner both as to ap-

pearance and convenience. My invention provides an attractive article of furniture which occupies a comparatively small amount of space and which may be readily positioned in such portions of a building in which the telephone is usually situated and which serves to support the telephone both while it is in use or disuse and which at the same time comfortably seats the user.

My invention comprises primarily a telephone stand A which includes a chair portion B associated therewith. This structure comprises front legs 10 and 11 and rear legs 12 and 13. The legs 10, 11, 12 and 13 are connected together by means of upper rails 14 while the legs 10 and 12 and the legs 11 and 13 are connected together by cross rails 15. In addition, a brace 16 connects the two rails 15 to provide a rigid and substantial structure. Upon the rails 14 is attached a seat 17 which projects outwardly beyond the legs 10 and 11 and the rails 14. This seat is mortised into the legs 12 and 13 which extend upwardly beyond said seat to form a support for a back 18 to the chair structure B.

The upper portions 19 and 20 of the legs 13 are enlarged as indicated in Fig. 1 and have positioned between them, two spaced partitions 21 and 22 arranged to form a vertical pocket 23. Upon the upper ends of portions 19 and 20 of legs 12 and 13 is attached a shelf 24 which has an elongated portion 25 connecting said legs and which has a circular portion 26 issuing outwardly beyond the leg 19 on the exterior thereof. The partition 21 is rabbeted into the portion 25 of shelf 24 and also into the seat 17 as indicated at 27 and 28. In a similar manner, the partition 22 is rabbeted into the portion 25 of shelf 24 as indicated at 30 while the lower portion of said partition terminates a short distance above the rearward portion 31 of seat 17 to form a space 32 communicating with the pocket 23. A slot 33 in the elongated portion 25 of shelf 24 communicates with pocket 23 and permits of inserting a telephone book such as indicated at 34 in Fig. 1, into said pocket. It will be noted that the height of the back 18 is such that when the ordinary telephone book is inserted into pocket 23, the lower edge thereof rests upon the rearward portion 21 of seat 17 with the upper portion of said telephone book projecting a short distance above the shelf 24. In this manner the tele-

- phone book is conveniently supported so that the same may be readily grasped by its protruding portion and removed from the pocket when desired for use. The opening 32 communicating with pocket 23, allows the dust, which may be accumulated within said pocket through the slot 33, to be removed from the rearward portion 31 of seat 17 where the same would be apt to settle.
- 10 The circular portion 26 of shelf 24 is arranged to permit of placing the ordinary desk telephone thereon and extends somewhat forwardly of the back 18 and outwardly beyond the leg 12 so that the same does not appreciably cover the seat 17. This portion of the shelf is constructed of such a size as to just receive the telephone base so as to be as inconspicuous as possible and to prevent the same from extending outwardly beyond the chair further than is necessary. Along the periphery of this portion of the shelf, I provide a rim 34 which may engage the edge of the telephone base to prevent the telephone from being accidentally shoved off the shelf 24. The portion 26 of shelf 24 being close to the leg 12 is counterbalanced by the remainder of the stand A and the chair structure B so that when the telephone, such as indicated at 35 in Fig. 1, is placed upon the same, the combined structure remains in stable equilibrium.
- Beneath the portion 26 of shelf 24, I position a tray 36 which is slidably mounted in a guideway 37 attached to the underside thereof. This tray is formed with upturned edges 38 forming a receptacle in which a pencil and pad or other writing articles may be placed for the convenience of the user. A stop 39 secured to tray 36 is movable along a slot 40 in the guideway 37 which serves to limit the movement of said tray in its extreme inner and outer positions.
- In the use of the invention, the structure is positioned with back 18 along the wall of the room in which the telephone is connected and within close proximity thereof so that the telephone may be placed upon the support 26 provided therefor. The user in seating himself, sits sidewise along the seat 17 with his right arm directly over the portion 25 of shelf 24. In this position he may readily remove the telephone book to ascertain the information he desires and replace the same within the pocket 23. On using the phone, it will be noted that the left hand of the user is conveniently positioned to the phone so that the receiver thereof may be removed and held in the left hand while the telephone is being used. If during the use of the phone it becomes necessary to write down any of the information received over the telephone the tray 36 may be slid out into its extended position as shown in Fig. 1 by the right hand of the user. This gives the user access to a pencil and pad of paper which may be placed on said tray and without interruption he may proceed to make the necessary notation while he is still holding the receiver in his left hand. If at any time the user desires to hold the telephone line open while leaving the phone, the receiver may be placed directly upon the tray 36 when in its extended position. While so arranged, the upturned edges 38 thereof prevent the same from being shoved off due to engagement with the earpiece of said receiver.
- My invention is highly advantageous in that it provides a simple and convenient construction whereby the telephone is held supported at all times and particularly when the same is being used. In the latter position, the mouth-piece of the telephone extends toward the user at approximately the proper height so that the most efficient use of the same may be had. At the same time the telephone book and writing materials are conveniently accessible when desired in connection with the use of the phone.
- Changes in the specific form of my invention, as herein disclosed, may be made within the scope of what is claimed without departing from the spirit of my invention.
- I claim:
1. A telephone stand including front and rear legs, said rear legs being enlarged along the upper portions thereof, spaced partitions secured to said legs between the enlarged portions thereof to form a pocket for the reception of a telephone book and a shelf mounted on the upper portions of said legs extending outwardly beyond one of said legs to form a support for a telephone, said shelf having a slot therein communicating with said pocket through which a telephone book may be inserted.
  2. A telephone stand including rear legs, said legs being enlarged along the upper portions thereof, spaced partitions immovably secured to said legs between the enlarged portions thereof to form a pocket for the reception of a telephone book, one of said partitions being shorter than the other, and a shelf secured to the upper portions of the said legs and extending outwardly beyond one of said legs to form a telephone support, said shelf having a slot along the same communicating with said pocket through which a telephone book may be inserted.
  3. A combination chair and telephone stand including a seat, front and rear legs attached to said seat, said rear legs extending upwardly beyond said seat, a shelf mounted upon the tops of and secured to said rear legs to form a top rail, said shelf extending outwardly beyond one of said rear legs to form a telephone support, front and rear substantially vertical partitions secured between said rear legs above said seat

in spaced relation to form a pocket for the reception of a telephone book, said front partition extending from said shelf to said seat, said rear partition extending from said shelf downwardly toward said seat and falling short thereof, said seat extending beneath said pocket to form a bottom therefor and a slot along the shelf registering with said pocket for the insertion of a telephone book therein.

4. A combination chair and telephone stand including a seat, front and rear legs attached to said seat, said rear legs extending upwardly beyond said seat, a shelf mounted upon the tops of and secured to said rear legs to form a rail therebetween, and front and rear substantially vertical partitions secured between said rear legs above said seat in spaced relation to one another to form a pocket for the reception of a telephone book, said seat extending below both partitions to form a bottom to said pocket and a slot formed in said shelf reg-

istering with said pocket for the insertion of a telephone book therein.

5. A combination chair and telephone stand including a seat, legs attached to said seat, two of said legs extending upwardly beyond said seat in spaced relation, said legs being provided with spaced facing grooves, a pair of partitions disposed within said grooves, a rail secured to the tops of said legs and having an opening therethrough registering with the space between said partitions, said rail being formed with rabbets along the edges of said opening to receive said partitions, one of said partitions extending from said rabbet to said seat and the other of said partitions extending from its rabbet to within a location falling short of said seat to provide an opening at the bottom of said partition communicating with the space between said partitions.

In testimony whereof I affix my signature.

JOHN ENGQUIST.
